UNITED STATES PATENT OFFICE.

ALAN R. FERGUSON, OF BUFFALO, NEW YORK.

TOY RAILWAY CROSSOVER.

Application filed February 3, 1923. Serial No. 616,647.

To all whom it may concern:

Be it known that I, ALAN R. FERGUSON, a citizen of the United States, residing at Buffalo, in the county of Erie and State of New York, have invented certain new and useful Improvements in Toy Railway Cross-overs, of which the following is a specification.

This invention relates to cross-overs for miniature or toy railways, an object thereof being to provide a cross-over adapted to be easily and effectively connected or joined to a plurality of toy track sections and which will be relatively cheap and easy to manufacture, strong, durable and efficient in use.

A further object of this invention is to provide a miniature cross-over section for a sectional toy railway having wire formed rails, in which the several sections form a portable structure adapted to be readily knocked down and assembled.

A further object of this invention is to provide an improved miniature cross-over having means for connecting a detachable third rail thereto and also having improved means for transmitting the current without interruption from one side to the other of the cross-over.

A further object of this invention is to provide a toy railway cross-over having rail portions stamped up from a single piece of sheet metal and constructed to form a durable and strong crossing member.

A further object of this invention is to provide a toy railway cross-over having means for releasably connecting the same to the ends of a plurality of track sections, and adapted to form a spring joint or wherein certain of the rail ends are adapted to be tensioned to form the joint.

A further object of this invention is to provide a toy railway crossing frog stamped up from a single piece of sheet metal.

Other objects of this invention will appear in the following description thereof, reference being had to the accompanying drawing forming a part of the specification wherein like reference characters indicate corresponding parts in the several views and wherein Fig. 1 is a perspective view illustrating an embodiment of my invention; Fig. 2 is a side elevation taken in section through line 2—2 of Fig. 1; Fig. 3 is a central longitudinal sectional view; Fig. 4 is a fragmentary plan view of the end of the

track section adapted to be joined to the cross-over; Figs. 5 and 6 are detail plan and side views respectively illustrating the third rail connections for the cross-over; Fig. 7 is a perspective view of a modified form of my invention; Fig. 8 is a central longitudinal sectional view of the cross-over; Fig. 9 is a perspective view of a part thereof; Fig. 10 is a perspective view of the terminal connections for the power rails of the several intersecting sections; and Fig. 11 is a perspective view illustrating a different means for joining the cross-over to a track section.

Before explaining in detail the present improvement and mode of operation thereof, I desire to have it understood that the invention is not limited to the details of construction and arrangement of parts which are illustrated in the accompanying drawings, since the invention is capable of other embodiments, and that the phraseology which I employ is for the purpose of description and not of limitation.

The construction shown in the drawings is for a right angled crossing but it will be understood that my invention is not limited to this form of crossing but may be of any angle or inclination.

Referring to Figs. 1 to 5 inclusive wherein I have illustrated a present preferred form of my invention it will be seen that the cross-over generally indicated at A may be readily formed by stamping or forming the same up out of a single piece of sheet metal previously cut to the required shape and form. In this manner a cross-over or toy railway crossing frog may be provided at a minimum of expense, due to the fact that the amount of material used is reduced to a minimum as well as the number of steps in the operation of forming the cross-over.

The cross-over A in the present instance is formed with four radiating arms 9 of similar construction and located at an angle to each other, herein shown at right angles to each other for the purposes of illustration. Each arm 9 comprises a base plate of suitable width having the side edges thereof bent up or coiled to form spaced ribs or rail portions 10. A pair of adjacent ribs or rail portions 10 intersect at 11 to form a right angled frog point. The cross-over also comprises a central plate or base portion 12 which connects together the several arms 9.

Between the central plate 12 and each arm 9 is formed a rib 13, these ribs being bent up from the metal. Each rib 13 terminates at opposite ends short of the frog points 11 so as to form spaces 14 therebetween for permitting the flanges of the car wheels to pass therebetween. The rail ribs 13 extend in prolongation of the rail portions 10, thus forming a complete cross-over constructed 10 integrally of the same piece of metal.

The coiled rail ribs 10 terminate at 15 intermediate the ends of the arms 9 and the end portion of each arm 9 has the lateral edges thereof extending outwardly at 16 15 beyond the plane of the ends 15 of the rail ribs 10. The portions 16 are thereupon bent upwardly and inwardly to form curved guide portions 17 for receiving the free ends of the rails of a track section. It will be 20 seen that the ends 18 of a track section 19 fit snugly between the curved guide portions 17 and extend in juxtaposition to the ends 15 of the rail ribs 10. Thus when the rail ends 18 are held between the partially coiled 25 guides 17, the same will extend in prolongation of the rail ribs 10, thus forming a continuous traction surface.

The end of each arm 9 forms substantially a guide plate for releasably interlocking the arm with a track section 19. In the present instance the interlocking connection or joint is substantially a spring joint and preferably includes lugs or projections 20 pinched outwardly from the rail ends 18 and 35 adapted to be inserted into openings 21 in the guide portions 17. In order to connect these parts it is necessary to contract or tension one or both of the rail ends 18 so as to permit the lugs 20 to clear the guide portions 17 and to spring into the openings 21. Each section 19 preferably comprises a pair of spaced wire rails 22 carried by supporting means. In order to provide a rigid, durable, and cheap construction the supporting 40 means preferably comprises spaced wire ties 23 to which the wire rails 22 may be spot-welded. The wire formed track section may be releasably connected to the end of an adjacent section by a similar spring joint, such 45 as for instance as described in my co-pending application, Serial No. 590,781, filed Sept. 27, 1922.

Where the cross-over is used in connection with electric toy railways having third or 55 power rails, the cross-over is provided with terminal connections for transmitting the current without interruption from one arm to the other. In the present instance each arm 9 is slotted transversely at 27 and a 60 metallic strip 28 extends underneath the central portion 12 of the device, passes up through opposed slots 27, and has the ends thereof bent over the inner edges of the slots as shown at 29. Suitable insulating strips 30 are interposed between the metal

strips 28 and the central portions of the cross-over, and it will be seen that the several strips 28 cross each other at the under side of the plate 12 and connect the opposite arms of the cross-over together.

A wire-formed third rail 31 is detachably connected to each arm 9 of the cross-over, the connections in the present instance being accomplished by means of spring clips 32. Each clip comprises a gutter or channeled portion formed by curved side walls 33 into which the wire 31 may be sprung and also readily released. The clip is bent over at 34 to form a hook portion which may be hooked over the end edge of the arm 9. A 80 suitable strip of insulating material 35 is interposed between the clip and the arm, the ends of the strip being folded under and the folded edge inserted within the bent portion 34 and held therein. When the third rail 31 is inserted in the gutter of the clip and the latter is connected to the arm 9, the end of the third rail projects beyond the clip and engages the inwardly bent portion 29 of a terminal strip 28, so that when the third rails are all in position the current will be transmitted by means of the crossed terminal strips 28 from one power rail to the other underneath the cross-over. Each power rail 31 is also detachably connected to its track section 19 by means of a duplex clip 36 having a gutter portion 37 adapted to be sprung over a wire tie 23 and also having a transverse gutter portion 38 into which the wire third rail 31 may be sprung. The gutter or clip portions 37 and 38 are interconnected in inverted relation and are preferably substantially duplicates and are insulated by means of a suitable strip 39. A further detailed description of this clip construction is 95 not deemed herein necessary as the same is fully described and shown in my co-pending application, Serial No. 590,781, filed Sept. 27, 1922.

The several arms 9 of the cross-over are 100 rigidly connected together by means of a curved or circular wire 40 which may be spot-welded as at 41 to the several arms 9 of the cross-over. The wire 40 is substantially the same size or diameter as the wire supporting ties 23 for the rails 22, so that by 105 means of this curved wire support 40 the rail portions of the cross-over will be spaced from the floor a distance substantially as great as the distance which the wire rails 22 are spaced from the floor. Since the rail portions 10 and 13 are bent up or formed so as to have a gauge substantially the same as the gauge of the wire rails 22 all of the rails of the track sections will be exactly 115 alined with the rail portions of the cross-over.

The central portion or plate 12 of the cross-over may be provided with a suitable central block 42. As shown in Fig. 3 the 120

central portion may be raised or bent up at 43 so as to have a height substantially the same as the height of the rail portions 10 and 13. This filler block or raised portion 42 forms a bearing surface for the third rail roller or wheel of the toy engine when the same passes between the ends of the third rails 31.

Referring to Figs. 7 to 10 inclusive, a somewhat modified form of cross-over is provided. In this instance the cross-over is provided with a central supporting plate 44 having the central portion thereof cut away at 55 and the edges thereof bent up or partially coiled to form spaced rail ribs 45 located at an angle to each other. To each corner of the plate 44 is secured as by welding a wire which is bent to form a frog point 46 and a pair of rail portions 47 and 48. The rail portions 47 are located in alignment with each other and with a rib 45, so that these parts form a continuation of the aligned rails of the track sections which are connected to the cross-over. To the outer ends of each pair of spaced rail portions 47 and 48 respectively is secured a guide clamp 49. This guide clamp 49 is provided with upwardly curved guide portions 50 adapted to receive the ends of the rail portions 47 or 48 which are preferably spot-welded thereto and the guide portions 50 project beyond the ends of the rails so as to receive the free spring ends 51 of a track section 52. In this instance the construction is substantially the same as hereinbefore described, the rails 51 preferably having lugs 52^a insertable, upon tensioning one or both of the rail ends, into openings 53, thus forming a spring joint.

When the cross-over is used with an electrical toy railway the same is provided with suitable terminal connections for transmitting power between the opposed third rails. For this purpose a piece of sheet metal may be cut to the required shape and is stamped up to form a central raised portion 54 adapted to extend into the central opening 55 in the plate 44. The hollow member 54 is provided with a plurality of radially extending arms 56 which extend in opposite directions across the under side of the base plate 44. Between the arms 56 and the base plate are interposed suitable strips of insulating material 59 and the arms are provided with lugs 57 which are clinched over the side edges of the plate 44. Each arm terminates in a spring contact member 58, and when the third rail 61 is connected to a guide clamp 49 by means of a spring gripping clip 60 which may be substantially the same as clip 32 hereinbefore described, the end of the third rail will bear against the spring contact member 58. In this manner the current will be transmitted between the separated ends of the opposed third rails.

If desired the cross-over illustrated in Fig. 1 may be used in connection with the conventional toy track sections in the manner shown in Fig. 11. In this instance the radial arms 9 of the cross-over may have each side edge thereof bent up so as to approximate more nearly a closed coil 62, or in other words the edges may be coiled around sufficiently to form holes adapted to receive dowel pins 63. The dowel pins 63 are set into the holes formed by the coiled edges of the arms so as to cooperate with the holes 64 in the conventional tin tracks 65. In this manner the cross-over may be readily adapted for utilization with various types of toy railways. It will of course be understood that the releasable connections shown in Fig. 11 may be reversed where desired, and the dowel pins 63 set into the holes 64 on the ends of the tin tracks and are insertable into the end holes of the coiled rail portions 62.

The third rail 31 or 61 may be suitably insulated from cross ties 23 by means of detachable strips 66 (see Fig. 1) having opposed notches 67 permitting the strips to be inserted and held between the main rails and cross ties.

As shown in Figs. 1 and 3 each arm 9 is also formed with lengthwise extending ribs 24, bent up from the metal, thereby increasing the strength and rigidity of the structure.

It is to be understood that by describing in detail herein any particular form, structure, or arrangement, it is not intended to limit the invention beyond the terms of the several claims or the requirements of the prior art.

Having thus explained the nature of my said invention and described a way of constructing and using the same, although without attempting to set forth all of the forms in which it may be made, or all of the modes of its use, I claim:

1. A toy cross-over for a toy railway comprising a piece of sheet metal bent or stamped up to form a pair of traction rail portions extending in alignment and spaced in accordance with the gage of the railway.

2. A toy cross-over comprising a sheet metal plate bent up to form a pair of main traction rail portions terminating in a frog point.

3. A toy cross-over comprising a piece of sheet metal having the side edges thereof bent or coiled to form parallel rail portions, said metal also bent to form a transverse rail portion spaced from said first rail portions.

4. A toy cross-over comprising a piece of sheet metal having certain edges thereof bent to form a pair of opposed crossing frogs.

5. A toy cross-over comprising a piece of

- sheet metal having certain edges thereof bent to form a pair of opposed crossing frogs and also bent to form a rail portion spaced from said frogs and extending in continuation of parts thereof. 5
6. A toy cross-over comprising sheet metal supporting means bent to form four pairs of converging rail portions. 65
7. A toy cross-over comprising a piece of sheet metal bent to form pairs of oppositely located crossing frogs, and also bent to form rail portions intermediate said frogs. 70
8. A toy cross-over comprising a base portion having a central opening therethrough, intersecting rails connected to said base portion, intermediate rail ribs between said intersecting rails, and a filler member extending through said central opening and having a height substantially the same as 15 said rail ribs. 75
9. A toy cross-over comprising pairs of rail sections having a plurality of intersecting points, a plate connected thereto, and having a part bent to form rail portions intermediate said intersecting points. 80
10. A toy cross-over comprising pairs of rail sections having a plurality of intersecting points, a plate connected thereto and having a part bent to form rail portions intermediate said intersecting points, and a 30 filler member extending upwardly from said plate and located between said rail portions. 85
11. In a toy railway the combination of a plurality of track sections, a crossing member having intersecting track sections, and means for connecting certain of said track sections together to form a spring joint. 90
12. In a toy railway the combination of a track section comprising a pair of spaced wire rails, and a crossing member adapted to be releasably connected thereto. 95
13. In a toy railway the combination of a pair of spaced wire rails, supporting means extending crosswise of the rails and to which 45 said rails are fastened, and a crossing member releasably connected to said rails. 100
14. In a toy railway the combination of a pair of spaced wire rails, supporting means extending crosswise of the rails and to which 50 the rails are fastened, and a crossing member releasably connected to said rails, said connection comprising a tension joint. 105
15. In a toy railway the combination of a crossing member, a track section, a power rail, and means for detachably connecting said power rail to said crossing member and track section. 110
16. In a toy railway the combination of a crossing member comprising a piece of sheet metal bent to form a plurality of rail portions, and a track section detachably connected to said cross-over and having a wire formed rail. 115
17. In a toy railway the combination of a track section comprising supporting means and a rail detachably connected thereto, and a crossing member also detachably connected to said rail. 120
18. In a toy railway the combination of a crossing member and a toy track section, 70 said member and track section having one a wire formed rail adapted to extend in prolongation of a rail of the other. 125
19. In a toy railway a crossing member comprising a plate having the side edges thereof bent or coiled to form parallel rail ribs, and a pair of rails detachably connected at the ends of said ribs, said plate having parts thereof bent to form guide portions adapted to receive the ends of said rails. 80
20. In a toy railway a crossing member comprising a pair of parallel rail portions terminating in a clamping member, and a pair of rails detachably connected to said clamping member. 85
21. A toy cross-over comprising a wire base, a crossing member mounted thereon and comprising a metallic plate having a part thereof bent to form a rail. 90
22. A toy cross-over comprising a wire base, a crossing member mounted thereon and comprising a metallic plate having a part thereof bent to form a pair of converging rails. 95
23. A toy cross-over comprising a wire base, a crossing member mounted thereon and comprising a metallic plate having a part thereof bent to form a pair of parallel rails and a transverse rail. 100
24. In a toy railway the combination of a crossing member and a plurality of rails detachably connected thereto, said rails and member having each wire formed supporting means. 105
25. A crossing member comprising a pair of coil-formed rails angularly related and intersecting to form a frog point. 110
26. A toy railway cross-over comprising wire formed supporting means, and a plurality of angularly related rails connected thereto. 115
27. A crossing member comprising four radiating arms, each comprising a plate having rails at the edges thereof and a lengthwise extending rib intermediate said rails. 120
28. A crossing member comprising four radiating arms, each comprising a plate having stamped up rails at the edges thereof, and a lengthwise extending stamped up rib intermediate said rails. 125
29. A crossing member comprising a central portion and rails extending therefrom, a plurality of conducting strips extending in opposite directions beneath said central portion and having the ends thereof projecting above said portion to form contacts. 130
30. A toy railway cross-over comprising a plurality of pairs of intersecting rails, and

wire formed means for connecting said pairs of rails together.

31. A toy railway cross-over comprising four radiating arms having spaced rails, and 5 wire formed means connecting said arms together.

32. A toy railway cross-over comprising a

wire bent into approximately circular form, and a crossing member secured to said wire.

Signed at 1822-3-4 Park Row Building, 10 New York, N. Y., this 31st day of January, 1923.

ALAN R. FERGUSSON.
